CABINET FOR ELECTRONIC EQUIPMENT

Charles E. Bozarth, Phoenix, Ariz., assignor to General
Electric Company, a corporation of New York

Filed Feb. 26, 1964, Ser. No. 78,788

Term of patent 14 years

(Cl. D26—5)

Fig. 1

Fig. 2

FIG. 3

FIG. 4

FIG. 1 is a top plan view of a cabinet for electronic equipment embodying my new design;

FIG. 2 is a perspective view thereof taken along the line 2—2 in FIG. 1;

FIG. 3 is a perspective view thereof taken along the line 3—3 in FIG. 1; and

FIG. 4 is a perspective view thereof taken along the line 4—4 in FIG. 1.

I claim:

The ornamental design for a cabinet for electronic equipment, as shown.
